(57) **CLAIM**

The ornamental design for a beam module toy brick with upstanding connectors as shown and described.

DESCRIPTION

FIG. 1 is a front perspective view of a beam module toy brick with upstanding connectors.

FIG. 2 is a front plan view of the beam module toy brick with upstanding connectors.

FIG. 3 is a back plan view of the beam module toy brick with upstanding connectors.

FIG. 4 is a first end plan view of the beam module toy brick with upstanding connectors.

FIG. 5 is a second end plan view of the beam module toy brick with upstanding connectors.

FIG. 6 is a top plan view of the beam module toy brick with upstanding connectors.

FIG. 7 is a bottom plan view of the beam module toy brick with upstanding connectors.

FIG. 8 is a bottom perspective view of the beam module toy brick with upstanding connectors.

FIG. 9 is a front perspective view of a second embodiment of the beam module toy brick with upstanding connectors.

FIG. 10 is a front plan view of the second embodiment of the beam module toy brick with upstanding connectors.

FIG. 11 is a back plan view of the second embodiment of the beam module toy brick with upstanding connectors.

FIG. 12 is a first end plan view of the second embodiment of the beam module toy brick with upstanding connectors.

FIG. 13 is a second end plan view of the second embodiment of the beam module toy brick with upstanding connectors.

FIG. 14 is a top plan view of the second embodiment of the beam module toy brick with upstanding connectors.

FIG. 15 is a bottom plan view of the second embodiment of the beam module toy brick with upstanding connectors; and, FIG. 16 is a bottom perspective view of the second embodiment of the beam module toy brick with upstanding connectors.

The broken lines in the figures show features of the beam module toy brick with upstanding connectors that form no part of the claimed design.
